ABSTRACT OF THE DISCLOSURE

A compact, highly reliable payout apparatus utilizing a unique electrical circuit to eliminate jackpotting and a gear drive which includes an overrunning clutch to prevent damage to the drive upon any jamming, which apparatus is extremely inexpensive and simple to manufacture, yet highly effective and reliable in operation.

This invention represents an improvement by simplification and cost over the coin payout mechanism shown in U.S. Patent No. 3,280,953. Essentially, the general object of the invention is to provide a highly reliable payout apparatus specifically for coins or other vending operation which is positive and not subject to jackpotting, yet which incorporates an extremely simple mechanical and electrical structure which is quite inexpensive. The device of the invention is completely immune from shock actuation and utilizes the theory that a bistable device must be reversed to keep the device from jackpotting so there can be no failure from without or within.

The aforesaid object of the invention and other objects which will become apparent as the description proceeds is achieved by providing a vending payout apparatus which includes the combination of a frame, a payout bar slidably carried by the frame, a motor mounted to the frame, gear means connecting the motor to the payout bar to effect substantially linear movement of the bar upon actuation of the motor, and means to energize the motor upon receipt of a proper vend pulse which is characterized by clutch means associated with the gear means to allow slippage upon any jamming of the payout bar.

For better understanding of the invention, reference should be had to the accompanying drawings wherein:

FIG. 1 is a top plan schematic representation of the gear train utilized to achieve drive from the motor to the payout bar;

FIG. 2 is an enlarged broken away cross-sectional representation of the clutch arrangement of one of the gears in the drive chain taken on line 2—2 of FIG. 1;

FIG. 3A and FIG. 3B are schematic illustrations showing the movement of the payout bar upon rotation of the end gears in the gear drive chain; and

FIG. 4 is an electrical schematic diagram of the electrical circuit utilized to drive the motor.

With reference to the form of the invention illustrated in FIG. 1 of the drawings, the numeral 10 indicates generally a frame which rotatably supports a plurality of gears indicated generally by numeral 12 and a drive motor indicated by a dotted line 14. Essentially, the drive motor rotates a small drive gear 16 which drives through a gear train 18, 20, and 22 to effect drive to a large idler gear 24. Idler gear 24 drives a second idler gear 26 and a slide bar drive gear 28 simultaneously with a second slide bar drive gear 30 being driven by idler gear 26, all as is quite clearly shown in FIG. 1 of the drawings. Essentially, drive of a slide bar, indicated in FIG. 1 by a dotted line 32, is achieved by each of the drive gears 28 and 30 mounting a drive pin 28a and 30a, respec-

tively which engage through appropriate slots 32a and 32b in the drive bar 32.

In order to achieve proper electrical actuation and drive to the motor 14 each of the drive gears 28 and 30 also has appropriate actuating pins 28b, 30b, and 30c, respectively. The pin 28b cooperates with an appropriate switch 40 while pins 30b and 30c cooperate with an appropriate switch 42, the function and operation of which will be more fully described hereinafter. Also, in order to positively limit the driving relationship of gears 28 and 30, pin 28b cooperates with a fixed stop 44 mounted to frame 10 while pin 30c cooperates with an appropriate stop 46 also fixedly mounted to frame 10. In other words, in the embodiment of the invention illustrated in FIG. 1, drive gear 28 cannot rotate any further in the clockwise direction thus limiting any further rotation of the other gears to drive gear 28 in the clockwise direction. Likewise, when pin 30c engages stop 46 upon rotation of the drive gear 30 in the clockwise direction, no further clockwise rotation of gear 30 will occur thus limiting the total movement of the gears in that direction since upon clockwise rotation of gear 30, gear 28 will be rotating in a counter-clockwise direction. Pin 30b does not cooperate with stop 46 in any manner, being purposely made somewhat shorter than pin 30c.

The rotation of gears 28 and 30 and the actual physical movement of slide bar 32 upon rotation thereof is most clearly shown in FIGURES 3A and 3B. Here it can be seen that the initial movement from an at rest position is as illustrated in FIG. 3A where gear 28 rotates in a counter-clockwise direction as indicated by the arrow and gear 30 in a clockwise direction, again as indicated by the arrow, which upon a 180° rotation of each gear, forces the slide bar 32 to the position shown in FIG. 3B to effect a desired payout. It is at this point that pin 30c will have engaged stop 46 limited the rotative relationship of gears 28 and 30. This causes actuation of switch 42 by pin 30b to reverse the direction of drive to motor 14, as will be more fully explained hereinafter, causing rotation of gears 28 and 30 in the opposite direction as indicated by the arrows in FIG. 3B, thus effecting return of the slide bar 32 to its initial position shown in FIG. 3A, whereby engagement of switch 42 by pin 30c stops the drive to motor 32, again as will be more fully explained with reference to circuit diagram of FIG. 4 hereinbelow.

In order to insure that with a gear drive such as illustrated in FIG. 1, the gears will not be stripped, and the mechanism severely damaged upon any possible jamming of bar 14 such as might occur when coins become jammed in the chute, or because someone is trying to defeat the payout or cause jackpotting to occur, a clutch mechanism is associated with gear 20 to allow motor 14 to drive without effectuating any driving movement to gears 28 and 30, and yet which clutch arrangement will insure a sufficiently positive drive when the mechanism is not jammed.

The details of this clutch arrangement is shown in FIG. 2 of the drawings which illustrates gear 20 mounted to a hub indicated generally by numeral 50. The hub 50 is rotatably supported by a spindle 52 which is mounted in any appropriate manner to frame 10 as by welding at 52a and 52b, for example. The spindle 52 might appropriately be made from suitable steel and have a smooth outer surface so as to allow smooth rotation of hub 50 therearound. The hub 50 comprises a small drive gear portion 50a on the lower end thereof and a reduced diameter bearing surface 50b on the upper end thereof. The lower gear portion 50a meshes with gear 22 while the annular open center of gear 20 is received in a forced

fit relationship over bearing surface 50b, as is clearly shown in FIG. 2.

With gear 20 being made from an appropriate plastic such as nylon having long wearing characteristics and some elasticity, a clutching engagement results between the bearing surface 50b and the annular opening through the center of gear 20. This frictional engagement is sufficient without any jamming to provide direct drive from gear 20 through gear 50a to gear 22. A Teflon clutch sleeve 50c facilitates the engagement of gear 20 with the shoulder of gear 50a. However, with any jamming of the slide bar 14, gear 22 will be stopped and held in a non-rotative relationship which thereby causes slippage between the surface of bearing 50b, sleeve 50c and the annular opening through gear 20 as gear 20 rotates around the hub 50 held in fixed relationship by the meshed engagement of gear 50a with gear 22. The sleeve 50c facilitates the sliding clutching action of the gear 20 to hub 50.

DESCRIPTION OF THE ELECTRICAL OPERATION

FIG. 4 illustrates the electrical schematic utilized to control interconnection between the motor 14 and switches 40 and 42. It should be noted that electrically switches 40 and 42 each comprise two independent switches 40a and 40b, and 42a and 42b, one of which is open dependent upon the actuation position of the switch. The switch 40 is appropriately called an in-cycle switch, as will be more fully explained hereinafter, and is illustrated in FIG. 4 in the actuated position. As soon as switch 40 de-actuates it shifts to the opposite position being spring loaded, and remains in the opposite position until actuated at the end of the cycle. Switch 42, on the other hand, is a double throw single pole switch which remains in the position to which it is actuated until it has been positively switched to the opposite position.

The circuit also includes a coin out switch indicated by dotted block 70 comprising an out switch 70a and validator power switch 70b. A suitable relay 80 controls contacts 80a, 80b, and 80c, respectively upon proper actuation thereof with each of the switches shown in their normal non-actuated positions, and which switches return to such normal non-actuated positions as soon as power is lost to the relay 80. A plurality of diodes 90, 92, 94, and 96 control and rectify the direction of current flow in the circuit from a 24 volt AC power source 98.

In order to provide a delay in the actuation cycle of relay 80 to insure an authentic vend pulse 100 is received, an appropriate capacitor 102 and resistor 104 are connected from the vend pulse to ground 106 to insure some current passage and time delay is provided to eliminate the possibility of actuation of relay 80 on a very short and improper vend pulse 100, caused by external shocked relay actuation.

A test switch 108 may be provided to check the operation of the circuit as this simulates the vend pulse 100 by connecting the 24 volt AC supply 98 to relay 80 by means of diode 92. In order to insure that the system will cut out upon overloading or jamming after a preselected period of time, a thermal motor protector indicated by dotted block 110 is provided which includes a resistance winding 112 and a normally closed switch 114 bimetallically actuated by excessive heating in resistance winding 112. An appropriate resistor 116 is connected from the in-cycle switch 40 to the motor protector 110 to give the entire circuit the appropriate tailored characteristics for the desired cycle lengths of the payout apparatus. An appropriate thermal motor protector might be one made by Hold-Heet, Inc., Ravenswood Ave., Chicago, Ill.

The coin out switch 70 is mounted on the face of the frame as indicated in FIG. 1 of the drawings and is depressed by the presence of appropriate coins or other media to be expended by movement of slide bar 32. In the actuated position, indicating the presence of coins or other media to be vended the validator switch 70b will be closed and the out of coin switch 70a will be open. This then allows the validator, which might be any ap-

propriate apparatus, such as that shown in U.S. Patent No. 3,360,653, to achieve validation to function since the machine now tells the validator that coins or other articles to be vended are present, and hence dollar bills, or other currency can be accepted by the validator for authentication. Naturally, when the coins are out, and switch 70 reverses, the bulb 70b will light showing the apparatus is out of coins, and the switch 70b will open thereby making it impossible for the validator to function by removing power.

With the foregoing description of the specific circuitry in mind, the actual operation of the circuitry will now be described. A vend pulse 100 is received through diode 90 to actuate relay 80. As mentioned above, there is a built in time delay before the actuation of relay 80 caused by the electrical characteristics of capacitor 102 and resistor 104. However, once relay 80 is actuated, it shifts contacts 80a, 80b and 80c from the positions illustrated in FIG. 4 to the opposite positions. This immediately allows the 24 volt AC input 98 to pass through reverse switch 42a, diode 94, and closed switch 80b through motor 14 and to ground 106. This starts rotation of motor 14 to drive gear 16 as seen in FIG. 1, and causes rotation of both drive gears 28 and 30, as described above. The actuation of relay 80 by vend pulse 100 is for a relatively short duration of time, such as less than 500 milliseconds, and the delay period by capacitor 102 and resistor 104, is normally between 10 to 100 milliseconds. However, the relay 80 is of the type that once contact 80a is closed, and power therefore is supplied directly from the 24 volt AC input 98 through a switch 42a, the relay will remain actuated even though the vend pulse 100 is terminated. Hence, current will continue to flow to motor 14 through 80b until drive gear 30 has proceeded 180° to cause actuation of reversing switch 42 which shifts switches 42a and 42b. As can clearly be seen from the diagram, as soon as switch 42a is opened, relay 80 will drop out causing switches 80a, 80b, and 80c to return to the original position shown in FIG. 4, and because switch 42b has now closed, power is now available through 42b, diode 96 and switch 80c to motor 14. However, because of the reversed position of diode 96, the current polarity to motor 14 is reversed, causing a reversed drive thereof and a return of the motor to the original shown in FIG. 4. However, because relay 80 is now de-actuated, no further current will be available to motor 14, and the drive will stop.

The in-cycle switch 40 having been actuated before any drive of motor 14 takes place immediately shifts as soon as motor 14 drives pin 28b off the switch causing switch 40b to open and switch 40a to close. Naturally, the opening of switch 40b breaks current through switch 70b, to the validator making it impossible for the validator to receive any further money or coins during the actual vend cycle. The connection of switch 40a into the circuit automatically actuates the resistor 112 of the thermal motor protector 110 placing this portion of the circuit into operation. In in-cycle switch will return to its initial position after the motor has driven the gears back to their initial position upon the 180° reciprocating movement.

The invention contemplates utilization of a direct current motor for motor 14, rather than a shaded pole motor thereby giving the motor good sensitivity to voltage reversal by the rectification of diodes 94 and 96. As is well known, it is a complex operation to switch the direction of drive in a shaded pole motor by reversal of current.

The diode 92 is provided to prevent feedback of the rectified AC vend pulse coming in through diode 90 into the remainder portion of the circuit, and to insure that it passes to actuate relay 80 if it is of proper strength and duration.

Therefore, it should be understood that the invention utilizes an extremely simple electrical circuit which requires positive reversal of motor 14 to complete a vend cycle, and which reversal is accomplished by mechanical actuation of a reversing switch in conjunction with a

unique gear train drive to change the circular motion of gears into linear motion for driving a slide bar. The clutching action present in the gear train prevents damage to the gears by jamming of the slide bar.

While in accordance with the patent statutes only one best known embodiment of the invention has been illustrated and described in detail, it is to be particularly understood that the invention is not limited thereto or thereby.

What is claimed is:

1. A vending payout apparatus which comprises, 10 a frame, a payout bar slidably carried by said frame, a motor mounted to the frame, and gear means connecting the motor to the payout bar to effect substantially linear movement of said bar upon actuation 15 of said motor, whereby at least one gear has a pin engaging the payout bar to provide linear motion to such bar upon rotation of said gear, means to energize the motor upon receipt of a proper vend pulse, switch means mounted to said frame engageable by said 20 gear upon a predetermined angular rotation thereof to reverse said motor and stop the drive of said motor upon its return to its original position.
2. An apparatus according to claim 1 where switch means are provided to insure against production of another vend pulse during the operation of the apparatus. 25
3. An apparatus according to claim 1 where the motor is a direct current motor, and includes rectifying diodes connected to the switch means to change the polarity of energization to the motor after an initial drive in one direction causes the gear means to engage the switch means.
4. A vending payout apparatus comprising a frame, a plurality of circular gears defining a train rotatably 30

mounted to the frame whereby two gears are mounted in spaced relation to rotate at the same speed upon driving of the train, means to rotatably drive at least one of the gears, pin means mounted at the same radial position on each of said two gears and extending substantially perpendicular to the surface thereof, and a payout bar slidably received by the frame, said bar having a pair of spaced aligned slots extending therethrough and each slot receiving a pin means therein whereby rotation of said two gears causes linear sliding movement of said payout bar, and characterized by

switch means mounted to the frame and actuated by one of said two gears to reverse the drive means and return the gears to their initial starting position.

5. An apparatus according to claim 2 where the means to rotatably drive is a direct current motor and includes rectifying diodes operating in conjunction with said switch means to reverse the polarity of the actuating current to the motor.
